UNITED STATES PATENT OFFICE.

LEMUEL PATTERSON, OF WARREN, PENNSYLVANIA.

LINING FOR WALLS.

SPECIFICATION forming part of Letters Patent No. 766,726, dated August 2, 1904.

Application filed February 3, 1904. Serial No. 191,814. (No model.)

To all whom it may concern:

Be it known that I, LEMUEL PATTERSON, a citizen of the United States, residing at Warren, in the county of Warren and State of Pennsylvania, have invented a new and useful Lining for Walls; and I do hereby declare the following to be a full, clear, and exact description of the invention, such as will enable others skilled in the art to which it appertains to make and use the same.

The invention relates to a lining for walls; and it has for its object to provide a simple, inexpensive, and efficient lining for brick and other masonry walls adapted to prevent dampness and sweating and capable of receiving a coating of plaster, wall-paper, or other wall-covering.

A further object of the invention is to provide a lining of this character adapted to be readily applied to a wall and capable of being securely fastened in position and adapted also to increase the strength of the structure on which it is employed.

With these and other objects in view the invention consists in the construction and novel arrangement of parts hereinafter described and shown, and particularly pointed out in the appended claims.

In the drawings forming part of this specification, and in which like numerals of reference designate corresponding parts, Figure 1 is a perspective view of a portion of a wall provided with a lining constructed in accordance with this invention. Fig. 2 is a detail perspective view of one of the blocks or sections, showing the front face thereof. Fig. 3 is a similar view showing the rear or inner face of the same. Fig. 4 is a perspective view of one of the fastening devices.

The lining which is designed to be applied to brick and other masonry walls is composed of blocks or sections 1 and 2 of square and oblong form, as shown, the square blocks being smaller than the oblong blocks and being arranged at the ends of the alternate tiers or rows in order that the latter may break joints with each other, as shown. The blocks are designed to be constructed of concrete or other plastic material and may be of any desired composition, and they may be molded in any

desired manner. They are provided at their corners with inwardly-extending lugs or projections 3, offsetting the body portions of the blocks or sections from the wall 4 to provide a continuous intervening air-space, whereby 55 dampness and sweating are effectually prevented. The oblong blocks are also provided at the centers of their opposite sides and edges with inwardly-extending lugs or projections 5, adapted to abut against the wall in the same 60 manner as the other lugs or projections 3. The blocks are firmly united by cement or similar adhesive or binding material and are provided with side and end grooves 6 and 7 for the reception of the same. 65

The blocks or sections 1 and 2 are securely secured to the wall by means of fastening devices 8 and are provided with corner notches 9, forming round holes when the blocks or sections are assembled, as clearly shown in 70 Fig. 1. The fastening devices, which are provided with suitable heads, have arrow-shaped spurs or wings 10 to prevent them from being withdrawn accidentally and to enable them to obtain a firm hold at the joints of the wall. 75 The oblong blocks or sections are provided at their sides with centrally-arranged slots 11, preferably adapted to form an opening of greater size than the shanks of the fastening devices and adapted to permit a limited adjustment of the same to enable the fastening devices to be properly driven into the joints of the walls irrespective of any slight variations in the distance between the same. The space around the fastening devices is designed 80 85 to be filled with cement, whereby the parts will be perfectly tight when the lining is complete.

The solid blocks or sections are provided at their outer faces with either smooth or rough surfaces, accordingly as they are designed to 90 receive a coating of plaster, wall-paper, or other wall covering or coating. The blocks, besides providing a perfectly dry wall, are adapted also to increase the strength of the structure to which they are applied. 95

What I claim is—

1. A lining for walls comprising a series of blocks or sections provided at their inner or rear faces with projections or lugs, arranged to fit against a wall to space the body portions 100

or sections therefrom, said blocks or sections being provided at their edges with registering notches forming openings and fastening devices adapted to pass through the openings
5 for securing the blocks or sections to a wall, substantially as described.

2. A lining for walls comprising blocks or sections having notches at their edges and provided in the latter with side and end grooves,
10 said blocks being also provided at their inner faces with projections or lugs to fit against a

wall, and fastening devices passing through the openings formed by the notches for securing the blocks or sections to the wall, substantially as described.

In testimony whereof I have hereto affixed my signature in the presence of two witnesses.

LEMUEL PATTERSON.
